United States Patent Office

Des. 214,827
Patented Aug. 5, 1969

214,827

HACKSAW OR SIMILAR ARTICLE

Sydney Jacoff, Mineola, N.Y., assignor to Great Neck
Saw Manufacturers, Inc., Mineola, N.Y., a corporation
of New York

Filed Aug. 30, 1968, Ser. No. 13,344

Term of patent 14 years

Int. Cl. D8—02

U.S. Cl. D8—96

FIG. 1 is a side elevational view of a hacksaw or similar article, showing my new design;

FIG. 2 is a top elevational view thereof;

FIG. 3 is a bottom elevational view thereof;

FIG. 4 is a rear elevational view thereof;

FIG. 5 is a front elevational view thereof;

FIG. 6 is a side elevational view thereof showing an element in an alternate adjustable position; and

FIG. 7 is a side elevational view thereof showing an element in another alternate adjustable position.

I claim:

The ornamental design for a hacksaw or similar article, substantially as shown and described.
